NAIL-SUPPLYING APPARATUS

Fred L. MacKenzie, Beverly, Mass., assignor to
 United Shoe Machinery Corporation, Paterson,
 N. J., a corporation of New Jersey

Application May 9, 1933, Serial No. 670,093

59 Claims. (Cl. 1-32)

My invention relates to the supplying of such fastenings as nails to machines by which they are to be driven. Said invention is of particular utility when it is desired to insert the supplied 5 nails in predetermined angular relations about their longitudinal axes.

For such work as the attachment of heels to shoes by nails driven from the inside of said shoes, it is desirable that the points of insertion 10 shall be close to the rand-crease, so a tight joint will be obtained. When thus driven, there is danger that the nail-points may emerge through the periphery of the heel unless precautions are taken to prevent this. One means to 15 this end involves the employment of nails of special forms, as those having beveled ends and which will run in a direction opposite to the bevel as they encounter the resistance of the heel-material in driving. Such nails, to obtain the 20 result sought, must be definitely positioned, and an object of this invention is to establish the desired relation and to thereafter maintain control of the position until the nails are ready to be driven. To achieve this end, as a feature of the 25 invention, the nails are taken as from a mass contained in a receptacle, all thus taken received and arranged in a single definite angular relation 30 about their longitudinal axes, and then discharged for driving while maintaining all such nails in the relation in which they have been arranged. The means by which the nails are herein shown as thus arranged may consist of a raceway provided with nail-positioning means included between raceway-sections, the nails, after 35 the positioning action, being delivered to a roll or other device which discharges them into tubes or conduits leading to a loader or transferring means, this in turn depositing the nails in passages in the nailing mechanism by which they 40 are to be driven. Throughout this travel, control of the nail-position is continuous, and delivery is made to the nailing mechanism with the heads and points in the correct relation. A well-known commercial nail has a head which is generally triangular in form and offset from the shank, and in connection with this nail the raceway may have grooves V-shaped in transverse 45 section, while the discharge-roll, tubes, loader and jack of the nailing mechanism may be provided with passages triangular in cross-section. Therefore, when the nails are properly presented 50 to any of these elements they are held by them against free angular movement. It is to be understood, however, that similar control of nails 55 of other forms than that having a triangular

head is within the scope of my invention. In the present embodiment of said invention, the nails have their points all turned in the same direction by their reception by a raceway-portion in which they hang by their heads, this delivering 5 to a portion in which the nails lie upon their sides and are positioned angularly. To prevent interference between the nails in the latter portion, they are preferably separated one by one from the first-mentioned portion and dropped in a 10 groove U-shaped in cross-section, which tends to turn them as they advance into the desired angular relation about their axes for reception by a terminal V-groove. From this last-mentioned groove the nails are discharged load by 15 load by the roll and into a tube previously mentioned. To overcome clogging and to insure the advance of the nails, especially in the slotted raceway and at the separator, the raceway is 20 preferably oscillated. The discharge-roll or device is shown as provided with a nail-retaining projection or finger movable into and out of the raceway. This finger, or the fingers, are so located that when the roll is making its delivery, the succeeding nail in each raceway is held clear 25 of the roll to be freed for advance as the roll is ready to receive it.

Other features of the invention of especial utility in connection with the organization just outlined, but capable of other applications, concern the manner of actuating the nail-separating means and nail-discharging means associated with the raceway, this involving more particularly their support and movement upon an oscillatory raceway; the mounting upon an arm, 35 upon which the raceway oscillates, of a tube or tubes which receive the nails discharged from said raceway; the arrangement of nail-retaining members or shutters individual to movable terminal sections of the conduits into which the 40 nails are discharged, the sections in the present instance being tubes adjustable upon a foot-plate and in which the conduits terminate; and the provision of a shutter or nail-retaining member 45 movable upon and individual to a transferring nail-holder or loader-block separable from its supporting and actuating loader.

In the accompanying drawings is illustrated a particular form of my invention applied to a machine for the attachment of heels by nails driven 50 from the inside of shoes. Here,

Fig. 1 shows the apparatus in broken side elevation;

Fig. 2 is a similar view of the upper portion of 55

- the work-supporting jack, together with a loader-block in nail-delivering position;

- Fig. 21, a broken side elevation of the loader-block; and
- 40 Fig. 22, a top plan view of said block.
- Referring to Figs. 1 and 3 for a general showing of the apparatus, we have at 30 the upper portion of the frame of a heel-attaching machine, which may resemble that disclosed in Letters Patent of the United States No. 1,785,928, Benjamin, December 23, 1930. Shoes to be heeled are placed upon a jack 32 rising at the front of the frame. The jack is preferably provided with adjustable tubes 34 (Figs. 2 and 10) in which the nail-drivers reciprocate, these tubes being movable to correspond to different nailing designs by the action upon them of crossed slots 38 in fixed cam-plates 38, 38 and a variable cam-plate 48. The latter is arranged to be shifted upon the jack by a screw 42. Such a structure is described in detail in United States Patent No. 1,269,654, Standish, June 18, 1918. A heel to be attached is held upon the heel-seat of a jacked shoe and the driving force resisted by a movable pressure-abutment 44 which engages said heel.
- The fastening which my improved apparatus is especially designed to supply is commonly known as a shovel-headed nail and is the subject of Letters Patent of the United States No. 1,761,119, Goulburn, June 3, 1930. This nail, appearing at N in Figs. 7, 12, 14, 15, and 16, has a beveled point *a* and a flattened, generally triangular head *b*, offset to the same side of the shank *c* as that at which the bevel *a* is situated and similarly inclined. The outer edge *d* of the head is furnished by one of the walls of the triangle. To obtain the desired inward inclination or toeing-in of the shanks away from the peripheries of the heels when the nails are driven, the bevels *a*, and therefore the head-edges *d*, should be held, when the nails are in the jack 32, outwardly toward the periphery of the jack-top. This relation is insured by making the passages 50 of the nail-tubes 34 triangular in horizontal section, as is best shown in Fig. 10 of the drawings, so rotation of the nails in the tubes is prevented. With this arrangement, it is only necessary to deliver the nails to these tubes at the proper angles about their longitudinal axes, and this end is attained by the present invention.
- The nails N to be supplied are contained in a mass in a drum 52 rotatable upon the frame 53 of a distributor, said nails being lifted by buckets 54 projecting inwardly from the circumferential drum-wall and dropped upon a grooved tray 56. The tray projects into the open inner end of the drum from a nailway, the frame of which appears at 58. This nailway is vibrated upon the frame 53 to produce advance of the nails along it and for this purpose is mounted upon transversely spaced rear rocker-levers 60 and a forward transversely-extended rocker-arm 62. Oscillation is imparted to the levers 60 by eccentric-rods 64 operated by eccentrics 66 upon a shaft 68 journaled in the frame and rotated through spur-gearing 70, a short horizontal shaft 72, bevel-gearing 74 and a vertical shaft 75 from the heel-attaching machine. Beneath the forward end of the tray is a series of separated raceways, corresponding in number to the jack-tubes 34 and each consisting of spaced bars 76 having at their upper edges inwardly and downwardly converging surfaces 78 arranged for engagement with the sides of the nail-heads *b*, the shanks *a* of the nails hanging in slots 79 between the bars. A portion of the nails advancing from the tray waste between the raceways, falling upon a chute 80 (Fig. 1) which returns them to the drum, but a sufficient number are caught in the raceway-slots and gather in series, all hanging upon the surface 78 with their points down, advancing under the influence of gravity and the vibration of the nailway-structure. From these raceways 76, the nails are picked off in groups or loads, one from each raceway, by a reciprocatory separator. The separating means which I have chosen to illustrate consists of the well-known type having a slotted plate 82 (Figs. 3, 5, and 6) mounted upon a carrier 84 to reciprocate across the raceways. A spring 86 produces the nail-separating travel of the plate. The manner of effecting the opposite or spring-compressing movement will later be described. Because of the peculiar form of the shovel-headed nail, they are liable to overlap and wedge in the raceway-slots 79 and to resist entrance into the slots of the separator-plate. This tendency I overcome by the oscillation of the nailway 58.
- Each nail, when released by a slot in the plate 82, falls through a passage 88 in an end-block 90 upon a downwardly and forwardly curved raceway-bar 92, this being one of a transverse series supported upon the nailway-frame 58. The nail-receiving groove 94 of each bar is shown as generally U-shaped in transverse section (Fig. 11). Under the momentum imparted by their fall and the shake of the nailway, the nails, supported at their heads and points, advance with considerable velocity into a groove 96 which continues each groove 94 in the corresponding bar 92. The groove 96 is preferably generally of V-form in cross-section, though its apex may be flattened to provide a contact-surface for the

nail-shanks *c*. The walls of this groove 96 preferably lie at substantially the same angle as to the side edges of the nail-heads. In the U-groove the tendency of the nails is to settle with the shanks down and to enter the V-grooves as shown in Figs. 12 and 16. This is the relation desired, and a corresponding control is maintained at every succeeding step of the advance until the nails are deposited in the passages of the jack 32. It may be, however, that a nail will become positioned with the edge *d* at its head turned down into contact with one of the walls of the groove 96, as appears in Fig. 14, instead of lying with the edge *d* upmost. To correct the position of such nails, there occurs at 98 a break in the V-groove. Here, at each side of the end of the groove 96, is a wall 100 starting at 102 outside said groove and curved inwardly and downwardly, these two walls converging to a succeeding raceway section in which is a V-groove 104 similar to the groove 96 and in substantial alinement therewith. If the nails leave the groove 96 correctly positioned with the edge *d* of the heads upmost, the walls 100 are without material effect upon them. If, however, said edge *d* is down it will strike one or the other of the walls 100 and be turned thereby about its longitudinal axis. Since the advance is relatively rapid, a sufficient impetus will be imparted to overturn the nail laterally, it entering the groove 104 with the head-edge *d* up in the chosen position.

The nails have arrived in the correct angular relation at the ends of the grooves 104 with their points in advance. They are now to be delivered to the jack 32 in successive loads, and with the heads down and the edges *d* of the heads lying toward the periphery of the jack-top. To discharge the nails heads-down in loads from the raceways, a roll 106 may be employed. In this roll are passages 108, triangular in cross-section to receive and hold the nails against rotation about their axes and extending part way through the roll. There is a passage 108 for each raceway 104, movable during the rotation of the roll 106 from approximate alinement with its raceway to a nearly vertical position in which the contained nails are dropped into tubes 110, the passage through each of these tubes being also triangular in cross-section and registering with the corresponding roll-passage in its discharging position to maintain the nails under control. At one extremity of the roll a spindle 112 turns in a sleeve 114 fixed horizontally in the nailway 58 by a set-screw 116 (Fig. 3). At the opposite end, the roll is separably coupled at 118 to a horizontal shaft 120 rotatable in the nailway. By loosening the screw 116 and taking out the sleeve 114, the discharge-roll may be removed for convenience in disassembling the tubes 110 and for clearing obstructions. Fixed to the roll 106 is a rearwardly extending yoke 122 from which depends a nail-retaining finger 124 for each raceway, each finger being arranged to enter its raceway at the space 98. The finger closes its groove 96 when the passage 108 is delivering to its tube 110. It rises from the raceway to permit the nails to enter the tube when the roll is turned to bring the passage into registration with the groove 104. The roll is operated in synchronism with the separator-plate in a manner which will now be described.

The actuating mechanism for the separator-plate and discharge-roll is best illustrated in Figs. 3, 4, and 5. The shaft 120 by which the

roll is rotated has fast upon it a bevel-gear 130 meshing with a bevel-segment 132 seured to a shaft 134 journaled in arms 136 extending from the nailway 58. Connected to the shaft and to one of the arms 136 is a torsion-spring 138, the effect of which, when put under tension, is to turn the roll-passages 108 into registration with the raceway-grooves 104 and to raise the stop-fingers 124. The extent of this movement is determined by a stop-screw 137. To tension the spring 138 and simultaneously compress the spring 86 to prepare for its separating action, there is supported upon the distributor-frame 53, projecting therefrom in proximity to one of the arms 136, a guide member 139 in ways in which an actuating plate 140 is horizontally movable. When the carrier 84 and separator-plate 82 are returned by the spring 86, the plate picks off a load of nails from the raceway-bars 76, so they are deposited in the grooves 94 for advance to the discharge-roll. Rotatable about a vertical axis at the inner edge of the plate 140 is a roll 141, which bears against a contact-surface upon the separator-carrier. This will transmit inward movement of the actuating plate to the carrier without interference with the oscillation of the nailway produced by the eccentrics 66. At the same time, a projection 142 from the upper edge of the actuating plate contacts with a short arm 143 extending from the shaft 134, revolving the segment 132 and turning the discharge-roll 106 as previously indicated. At the forward side of the actuating plate 140 is a contact-projection 144 in which is a depression 146. Arranged to enter the depression is a hook 148 pivoted upon the vertical arm of a bell-crank-lever 150 fulcrumed on the frame 53, the hook being held normally depressed by a torsion-spring 152. To a horizontal arm of the bell-crank is articulated a link 154 joined at its lower extremity to a bell-crank-lever 156 fulcrumed upon the frame 30. The arm of the lever 156 opposite the link-connection carries a roll 158, held by a spring 160 surrounding the link against the periphery of a cam 162 rotatable by a shaft 163. The turning of this cam to cause a nail-delivering operation is controlled through movement by the operator of a hand-lever 164, as in the Benjamin patent previously mentioned. A rod 166 has at its upper end a vertical slot 168 at the bottom of which rests a projection 170 from the front of the hook 148. The rod is pivoted at its lower extremity to swing in directions at right angles to each other upon an arm 172 secured to the end of a shaft 174 lying transversely of the frame 30. At its opposite extremity the shaft 174 has fast upon it an arm 176 (Fig. 1), which, through a spring 178 and a rod 180 which said spring surrounds, may be yieldably raised when the heel-attaching machine is operated to drive into the jacked work the heel-attaching nails. This last-mentioned mechanism is more fully disclosed in an application for Letters Patent of the United States filed in my name on June 7, 1932, and bearing the Serial No. 615,834. On February 20, 1934, this application became Patent No. 1,947,770. Elevation of the rod 166 forces the bottom of the slot 168 against the hook-projection 170, raising the point of the hook into engagement with an inclined surface 182 on the plate-projection 144. This presses aside the plate 140 and the separator-carrier 84 against the force of the spring 86, and allows the hook to enter and be temporarily retained by the plate-depression 146. Simultaneously with the

raising of the hook, an arm 184 secured to the rod 166 is brought against one extremity of a latch 188 upon one of the arms 136. This latch is provided with a shoulder 190, which is 5 normally elevated by a spring 192 for engagement with a contact-finger 194 projecting from the shaft 134 opposite the arm 143. The latch-shoulder, by its engagement with the finger 194, holds the shaft 134 against rotation by the spring 10 138 with the discharge-roll passages 108 in their vertical relation to deliver to the tubes 110 the contained nails, and with the fingers 124 preventing entrance of the nails to the raceway-grooves 104. Then, upon elevation of the rod 15 166, the arm 184 thereon trips the latch, and the spring rotates the roll so its passages are carried to the nail-receiving position, the fingers being raised from the raceways.

The group of tubes 110, which receive the nails 20 from the discharge-roll, are mounted upon the rocker-arm 62 as a separable unit. A holder-frame 200 (Figs. 3 and 6) is clamped to opposite sides of the arm by overhanging plates 202, 202. The upper portion of the holder is extended horizontally in the form of a bar 204 provided with spaced vertical openings in which the tubes are 25 secured by screws 206. A block 208 furnishes the lower portion of the holder, the tubes converging to an arrangement which may be substantially 30 the means of the various nailing designs which are to be employed. Screws 210 fasten the tubes in the block. These tubes 110 have joined to them flexible extensions 212 through which are triangular passages placed similarly to those 35 of the tubes, and the extensions are connected to the upper extremities of foot-plate-tubes 214 which may be positioned to correspond to each of the nailing designs to be employed. In their descent from the bar 204, the tubes 110 are so 40 twisted about their longitudinal axes that the conveyed nails, which all left the discharge-roll 106 with their head-edges α disposed rearwardly, are rotated until such edges assume substantially 45 the positions in which they are to be inserted in the work; that is, turned outwardly from the center of the group. If it is desired to remove the tubes 110 for clearing, as in case one or more become clogged, the set-screw 116 is loosened, the sleeve 114 withdrawn and the discharge-roll 50 106 lifted out. Then, upon loosening the clamping plates 202, the holder 200 with the entire tube assembly may be removed, the flexible extensions 212 leaving the tubes 214.

Considering the adjustment of the tubes 214, 55 these, as appears in Figs. 1, 3, 8, and 17, are a part of a foot-plate-structure designated as a whole by the letter P. A bracket 220 extends at one side of the frame 30 and contains vertical ways 222 to receive a support 224. Between horizontal arms 226 of this support are mounted fixed plates 228, 228 spaced from each other, between which plates are guided flanges 230 upon terminal tubes 232 in which the tubes 214 are fixed. In these tubes 232 are triangular passages 233, continuing those of the tubes 214 and in the same angular relation. The terminal tubes above and below the flanges pass through pairs of registering cam-slots 234 in the plates 228, 228. At the 60 top of the upper plate 228 slides an adjusting plate 236, provided with slots 238 receiving the tubes and lying across the slots 234. A screw 240 turning in the support 224 is threaded into a lug 242 rising from the plate 236. When said 65 plate 236 is moved forwardly or rearwardly by

the screw, the co-operating slots will cause the tubes 232, 214 to be shifted along paths which contain the nail-inserting positions of all nailing designs and maintained in the proper relation to each other. This mechanism is similar to that 5 for adjusting the jack-tubes in the Standish patent already referred to.

The nails are to be held in the foot-plate-tubes after they have been received, for delivery therefrom at a definite point in the cycle of operation. For this purpose, nail-retaining means is provided, and it is important that the nail-releasing movement shall be of limited extent for all adjustments of the tubes, so the nail-delivery shall be prompt and readily obtained 10 with a limited actuating movement. To this end, the tubes are preferably provided with nail-retaining shutters individual to and movable with them. Referring particularly to Figs. 18, 19, and 20, each terminal-tube 232 has at its foot a lateral enlargement 244 containing a channel open at the bottom, and in which is arranged to reciprocate a shutter 246 having a reduced tongue 248 normally extending into the passage 233 and serving to support the nails. From the 15 shutter depends a projection 250, which is received by a slot 252 in an actuating plate 254 guided upon the arms 226 below the lower plate 228 (Fig. 8). Each slot 252 is of such length as 20 to receive its shutter-projection in all tube-positions. Parallel to each slot 252 is a slot 256 through which nail-delivery is made. Both the slots 252 and 256 are parallel to the corresponding slot 234 in the lower plate 228. It will be 25 seen that with this arrangement, for any position of the tubes 232, movement of the plate 254 to the right, as viewed in Fig. 18, will cause each projection 250 to be engaged by the edge of its slot 252. The corresponding shutter will therefore be operated to free the tube and allow the 30 supported nail to drop through the slot 256, the width of which is sufficient to permit this in all 35 positions of the plate.

The mechanism for actuating the plate 254 is not a feature of the present invention, a similar 40 mechanism for actuating a shutter being disclosed and claimed in the previously-mentioned Patent No. 1,947,770 and covered in part in an application filed in my name February 14, 1930, Serial No. 428,529. The resulting patent is No. 45 1,947,769, dated February 20, 1934. Briefly, it may be said that the plate is joined by a link 258 (Fig. 1) to a lever 260 fulcrumed upon the frame 30, and provided with a lateral projection 262 entering a fork in an upwardly-extending 50 arm of a three-armed lever 264 turning at one side of the lever 260. With the upper edge of a forwardly-extending arm of the lever 264 operates a latch 266, while a rearwardly-extending arm carries a roll 267 arranged for engagement with the upper edge of a loader-slide 258 55 reciprocating horizontally in the frame 30. At the forward extremity of the slide is a frame 270 (Figs. 21 and 22) to receive a loader-block 272, which may be one of an interchangeable 60 group, each block having a plurality of vertical nail-holding passages 274 arranged in accordance with a particular nailing design. A spring-actuated pin 276 secures any one of the blocks of the group separably in the frame. In the 65 rearward position of the loader-block its passages 274, which are triangular in horizontal section, register with the foot-plate-tubes 232, when these are set to the same design. From 70 this nail-receiving position the loader-block is 75

given a forward transferring movement, to bring its passages 274 into nail-delivering alinement with the passages 50 of the jack-tubes 34, by gearing 278 actuated, as in the Benjamin patent, from the shaft 163 under the control of the hand-lever 164. When the loader-block is in nail-receiving position beneath the foot-plate, a depression 280 in the upper edge of its slide 268 lies beneath the roll 267, but, until nail-delivery is to be made, movement of the lever 264 is prevented by the presence of the latch 266 above the forward arm of said lever. By thus retaining the lever, the plate 254 is prevented from being moved by a spring 282 to open the foot-plate shutters 246. The spring connects the plate and latch, drawing the latter into its active position. Upon the rod 180, which, as already pointed out, rises when the heel-attaching machine operates, is a contact-member 284. This strikes the tail 20 of the latch, turning it anticlockwise (Fig. 1) to release the lever 264. Since the depression 280 is beneath the lever-roll 267, this lever and the lever 260 are free to turn clockwise, so the spring 282 moves the plate 254 to cam open the shutters 246. The nails contained in the foot-plate-tubes 232 therefore drop into the loader-block-passages 274. Had the loader-block been out of registration with the foot-plate-passages, the loader-slide-depression 280 would have been at one side of the roll 267, and the horizontal surface of the slide would have prevented rotation of the lever 264 and the opening of the shutters. After the reception of the nails by the loader-block, the forward travel of the slide for the delivery of the nails to the jack forces the roll out of the depression. This causes the lever 260 to impart to the plate 254 its shutter-closing movement and lowers the forward arm of the lever 264, so the latch 266 moved by the spring 282 engages and retains it.

The nails, upon entering the loader-block-passages 274, must be releasably held while the block advances over the jack and are there delivered to the passages 50. Guided in ways upon the under side of the block 272 is a retaining plate or shutter 290 in which is a triangular opening 292 corresponding to each passage 274. The shutter is normally held with the openings 292 at one side of the passages 274, so the latter are closed, by a spring 294 connecting the shutter to the frame 270. This is as illustrated in Figs. 21 and 22 of the drawings. When the loader arrives at the jack, a projection 296, depending from the rear of the plate 290 strikes the jack and causes said plate to be held back, and when the forward travel of the loader ceases the jack-passages 50, the shutter-openings 292, and the loader-block-passages 274 are all in substantial registration. Thus the nails are released and fall into the jack ready for insertion. When the loader leaves the jack to return to its nail-receiving position, the spring 294 closes the shutter ready for the reception of the succeeding load of nails from the foot-plate. It should be observed that the shutter of the loader-block is individual to it. As a result of this, the travel necessary to release the supported nails may be minimized. Because of this, said release is quickly effected, and without the nail-displacing shock which might follow the tripping of a shutter movable upon the loader-frame and spring-actuated through a considerable distance to cover all nailing designs.

The operation of the apparatus will now be outlined. By the screws 42 and 240, the jack-

tubes 34 and the foot-plate-tubes 232 will have been respectively adjusted to the nailing design best suited to the form of the heel to be attached, and a corresponding loader-block 272 carrying its shutter 290 placed in the frame 270. At the beginning of an operating cycle the loader-block, with its shutter closed, is resting beneath the foot-plate P and contains a load of nails N with their heads b resting upon the shutter, the head-edges d being turned outward. The roll 267 is seated in the depression 280 in the loader-slide 268, its lever 264 being free from the latch 266. The shutters 246 of the foot-plate-tubes 232 are therefore open. The discharge-roll 106 has its passages 108 alined with the raceway-grooves 104 and contains a load of nails, the nail-retaining fingers 124 being raised to free the raceways. The nail-drum 52 and the nailway 58 are in constant motion, the raceway-slots 79 containing series of nails hanging by their heads upon the bar-surfaces 78 and held back by the separator-plate 82. The operator, holding a shoe to be heeled, shifts the lever 164. This causes the rotation of the shaft 163 and, through the gearing 278, the advance of the loader-block. The roll 267 is at once cammed out of the depression, shifting the actuating plate 254 to close the foot-plate-shutters. When the loader-block reaches the jack 32, the contact of its shutter-projection 296 with said jack frees the contained nails and they fall into the pack-passages 50. Both the loader-block-passages 274 and the jack-passages 50, by their triangular form and like angular relation about the vertical axes, position each nail of the delivered set with its beveled point a and the head-edge d turned outwardly toward the periphery of the jack. There is thus insured the inward deflection of the nails away from the periphery of the heel to be attached and the proper engagement of the nail-heads with the curved heel-seat of the shoe. While this nail-delivering movement is being made by the loader, the cam 162 is being rotated by the shaft 163, causing oscillation of the lever 150. The hook 148 joined to this lever was left at the termination of the previous cycle resting in the depression 146 of the actuating plate 140. The lever consequently moves the plate to the right (Fig. 3) and, through the roll 141, shifts the carrier 84 to move the separator-plate 82 across the raceway-slots 79. The contour of the cam then permits the actuating plate, carrier and separator to be moved reversely by the spring 86. During the travel, under the influence of the spring, the separator picks off a load of nails from the raceways and drops them into the passages 88, this occurring toward the end of the reciprocation. At this time, the hook 148 is released from the depression 146, because the extent of travel of the hook to the left is greater than that of the plate 140. In the advance of the plate, its projection 142 revolves the segment 132, thus turning the discharge-roll 106 to deliver its contained nails to the tubes 110 and lowering the fingers 124 into the raceway-spaces 98. In this position, the roll and fingers are retained by the shoulder 190 of the latch 186. The nails released by the separator-plate 82 pass down the U-grooves 94. The steepness of inclination of these causes the nails to enter the V-grooves 96 at a considerable velocity and with a tendency to settle with their shanks in the desired definite position at the bottoms of the grooves with the edges d of the heads upmost. At the forward extremities of the grooves 96 this single load of nails is stopped by 75

the depressed fingers 124. It is to be noted that in each raceway between the plate 182 and the roll 106 there is never more than a single nail. Therefore, interference cannot be produced by 5 one nail riding over another.

After the operator has thrown the lever 164 and thus supplied a load of nails to the jack 32, he places the shoe which he holds upon said jack, applies a heel to its heel-seat, and depresses a 10 treadle to lower the abutment 44 into contact with the work and to start the heel-attaching machine in operation. As a consequence of this 15 operation, the heel-attaching nails are driven into the work and the rod 189 is elevated under the power of the machine. In this upward movement, the rod-projection 284 unlatches the lever 260, and, the loader being in the correct receiving 20 position, the roll 267 enters the depression 280. The plate 254 is therefore shifted by the spring 25 282 so the nails supported by the shutters 246 are allowed to drop into the loader-block-passages 274. The rod 189 also rotates the shaft 174 to lift the rod 166. This, by engagement with the projection 178 causes the entrance of the 30 hook 148 into the depression 146 of the plate 142, in preparation for the actuation of the separator 82 and the discharge-roll 106 during the next operating cycle. The arm 184 upon the rod 166 lifts the latch 186, releasing the shaft 134 so the 35 spring 138 rotates the discharge-roll rapidly to raise the fingers 124 from the raceways and bring the passages 108 into alignment with the grooves 104. The nails, thus freed by the fingers, advance under the influence of the raceway-oscillation into the grooves 104. If the nails are mis-positioned in the grooves 96, they will be turned by the curved surfaces 100 so they will unfailingly enter the grooves 104 with the shanks down. 40 As these last-mentioned grooves are short, the nails are at once received by roll-passages 108 in the chosen relation. In spite of the relatively short distance which the nails have to travel after they leave the fingers, the roll will have been sufficiently rotated to receive them because of the 45 quickness with which the spring 138 acts. When the nails are discharged by the roll during each cycle, constant control of the angles about their longitudinal axes is maintained in the tubes 110, 212, 218 and 232 furnishing the conduit system, 50 because they are held against free rotation by the contact of their heads with the walls of the triangular passages. They therefore arrive in the loader-block-passages 274 and are delivered to the jack-passages 58 correctly positioned, as 55 already described. This can occur only after the previously supplied nails have been driven out of the jack-passages. Double loading is therefore impossible. As soon as the nailing operation has been completed, following the starting 60 of the heel-attaching machine, the abutment 44 rises, the operator removes the shoe from the jack, and the apparatus is ready for the next operation.

Having described my invention, what I claim 65 as new and desire to secure by Letters Patent of the United States is:

1. In a nail-supplying apparatus, a receptacle in which nails are contained in a mass, means for receiving nails from the receptacle and arranging all in a single definite angular relation about their longitudinal axes, and means for discharging the nails from the receiving means while maintaining for all the same angular relation in which they have been arranged.
2. In a nail-supplying apparatus, a receptacle

in which nails are contained in a mass, means for receiving nails from the receptacle and arranging each in a definite angular relation about its longitudinal axis, means for discharging the nails from the receiving means while maintaining such angular relation, and nail-retaining means movable into and out of the receiving means at the rear of the discharging means. 5

3. In a nail-supplying apparatus, a receptacle in which nails are contained in a mass, means 10 for receiving nails from the receptacle and arranging each in a single definite angular relation about its longitudinal axis, means for discharging the nails from the receiving means while maintaining such angular relation, and conduits 15 into which the nails are discharged, said conduits contacting with the nails to maintain them against free rotation.

4. In a nail-supplying apparatus, a receptacle in which nails are contained in a mass, means 20 for receiving nails from the receptacle and arranging each in a definite angular relation about its longitudinal axis, means for discharging the 25 nails from the receiving means while maintaining such angular relation, and conduits into which the nails are discharged, said conduits being twisted about their longitudinal axes to turn the nails while maintaining them against free rotation.

5. A nail-supplying apparatus, a receptacle in 30 which nails are contained in a mass, means for receiving nails from the receptacle and arranging each in a definite angular relation about its longitudinal axis, means for discharging the nails from the receiving means while maintaining such 35 angular relation, conduits into which the nails are discharged, said conduits contacting with the nails to maintain them against free rotation, and a transferring member provided with passages into which the conduits deposit the nails, said 40 passages holding the nails against rotation about their axes.

6. In an apparatus for supplying nails having 45 triangular heads, a raceway having a V-groove to which the nails are delivered, means for turning the nails to enter the V-groove in a definite angular relation, and an oscillatory discharge-roll 50 provided with a passage triangular in cross-section and receiving nails from the V-groove.

7. In an apparatus for supplying nails having 55 triangular heads, a raceway having a V-groove to which the nails are delivered, means for turning the nails to enter the V-groove in a definite angular relation, an oscillatory discharge-roll 60 provided with a passage triangular in cross-section and receiving nails from the V-groove, and tubes having passages triangular in cross-section and into which the discharge-roll deposits the nails.

8. In an apparatus for supplying nails having 65 triangular heads, a raceway having a V-groove to 70 which the nails are delivered, means for turning the nails to enter the V-groove in a definite angular relation, an oscillatory discharge-roll provided with a passage triangular in cross-section and receiving nails from the V-groove, tubes having passages triangular in cross-section and into which the discharge-roll deposits the nails, and a reciprocating loader-block provided with passages triangular in cross-section and receiving the nails from the tubes.

9. In an apparatus for supplying nails having 75 triangular heads, a series of parallel raceways each having a V-groove and to which the nails are delivered, means associated with each raceway for turning the nails to enter the V-groove 70

in a definite angular relation, a nail-transferring member provided with triangular passages arranged in accordance with a nailing design, and tubes triangular in section and twisted about their longitudinal axes, said tubes conducting to the transferring member the nails discharged from the raceways and simultaneously rotating them for delivery in a definite angular relation.

10. In nail-supplying apparatus, nail-transferring means, a raceway provided with a supporting surface upon which nails rest in a series, means for releasing the nails one by one for travel through the raceway, and means movable at the end of the raceway for controlling the discharge of nails therefrom to the transferring means.

11. In nail-supplying apparatus, nail-transferring means, a raceway, means for releasing the nails one by one for travel through the raceway, means movable at the end of the raceway for controlling the discharge of nails therefrom to the transferring means, and nail-retaining means movable into the raceway under the power of the apparatus during the discharge of the nails.

12. In nail-supplying apparatus, a nail-receptacle, a slotted raceway receiving nails from the receptacle and supporting them for travel hanging by their heads, a nail-separator movable at the forward extremity of the slotted raceway, a raceway upon which the nails are dropped by the separator and over which they pass lying upon their sides, and a roll to which the last-mentioned raceway delivers and by which the nails are discharged to the transferring means.

13. In nail-supplying apparatus, nail-transferring means, a nail-receptacle, a raceway to which the receptacle delivers, means for releasing the nails one by one for travel through the raceway, means movable at the end of the raceway for controlling the discharge of nails therefrom to the transferring means, and means included in the raceway for determining the angular position of the nails about their longitudinal axes.

14. The combination with nail-inserting mechanism, of a receptacle in which headed nails are contained in a mass, means for receiving nails from the receptacle and arranging each with a definite angular relation of the head about the longitudinal axis of the shank, and means for transferring the nails to the inserting mechanism while maintaining control of their angular position.

15. In an apparatus for supplying nails having heads offset from the shanks, a raceway provided with means for supporting the nails with the heads in one direction only and with means for holding said nails with the heads in definite angular positions circumferentially about the axes of the shanks.

16. In an apparatus for supplying nails having heads of generally triangular form, a raceway having a section in which the nails are arranged with their heads in a predetermined direction and a succeeding section provided with walls upon which the nails lie on their sides with adjacent sides of the triangular heads in contact with said walls.

17. In an apparatus for supplying nails having heads offset from the shanks, a nail-receptacle, a slotted raceway to which the receptacle delivers, and a raceway having V-grooves receiving nails from the slotted raceway.

18. In a nail-supplying apparatus, two raceway-sections, and means situated between the sections and engaging the heads of the nails for

turning said nails about their longitudinal axes.

19. In an apparatus for supplying headed nails, two raceway-sections upon which nails advance supported at their heads and points, and means situated between the sections and acting upon the nail-heads for turning the nails about their longitudinal axes.

20. In an apparatus for supplying headed nails, two raceway-sections upon which nails advance supported at their heads and points, means situated between the sections and acting upon the nail-heads for turning the nails about their longitudinal axes, and nail-retaining means movable into and out of the raceway at the turning means.

21. In a nail-supplying apparatus, two raceway-sections, one delivering to the other, and curved walls situated between the sections at each side of the path of the nails, said walls being more widely separated than those in the delivering section, they converging inwardly and downwardly and merging into the walls of the receiving section.

22. In a nail-supplying apparatus, a slotted raceway, a raceway of U-shaped transverse section to which the slotted raceway delivers, and a raceway of V-shaped transverse section to which the U-raceway delivers.

23. In a nail-supplying apparatus, a slotted raceway, a raceway of U-shaped transverse section receiving nails from the slotted raceway and being curved downwardly and forwardly therefrom, means for dropping the nails one by one upon the U-raceway, and a raceway V-shaped in transverse section to which the nails are delivered under the impetus acquired in their descent over the U-raceway.

24. The combination with nail-inserting mechanism having nail-receiving passages engaging the contained nails to hold them in a definite angular relation about their longitudinal axes, of a receptacle in which nails are contained in a mass, means for receiving nails from the receptacle and positioning them in a definite angular relation about their longitudinal axes, and means for conducting the nails from the positioning means to the inserting mechanism and for maintaining constant control of their angular position until they are delivered to the nailing mechanism.

25. The combination with a jack provided with nail-passages triangular in cross-section, of a receptacle in which nails are contained in a mass, means for receiving the nails and positioning them in a definite angular relation about their longitudinal axes, V-raceways to which the positioned nails are delivered, and a series of conducting members connecting the raceways and jack-passages and all having triangular passages.

26. In a nail-distributor, an oscillatory raceway having slots arranged to receive and conduct nails hanging by their heads, there being means associated with the raceway for arranging the nails in a definite angular relation about their longitudinal axes, and means for oscillating said raceway.

27. In a nail-distributor, an oscillatory raceway having slots arranged to receive and conduct nails hanging by their heads, a nail-separator mounted to reciprocate on the raceway and having slots to receive the shanks of the nails, and means for oscillating said raceway.

28. In a nail-distributor, an oscillatory raceway, a nail-separator movable upon the raceway, a discharge device movable upon the raceway, and nail-turning means interposed between the separator and discharge device.

29. In a nail-distributor, an oscillatory raceway arranged to support nails in a series, means movable upon the raceway for separating the nails one by one from the series, and means movable upon the end of the raceway for discharging the nails therefrom. 5
30. In a nail-distributor, a raceway, a nail-separator movable upon the raceway, a discharge device movable upon the raceway, and nail-retaining means movable toward and from the raceway between the separating means and discharge device. 10
31. In a nail-distributor, a raceway, a discharge device movable upon the raceway, and nail-retaining means carried by the discharge device and movable into and out of position to be engaged by the nails upon the raceway. 15
32. In a nail-distributor, a raceway arranged to support nails in a series, a plate slidable upon the raceway to separate nails one by one from the series and deliver them for support upon the raceway, and a discharge-roll rotatable at the end of the raceway and into which the nails enter while still supported on said raceway. 20
33. In a nail-distributor, a raceway arranged to support nails in a series, a plate slidable upon the raceway to separate nails one by one from the series, a discharge-roll for the nails rotatable at the end of the raceway, and a nail-retaining finger projecting from the roll and movable thereby into and out of position to be engaged by the nails in the raceway. 25
34. In a nail-distributor, a frame, a raceway arranged to oscillate upon the frame, a nail-separator mounted to reciprocate upon the raceway, a reciprocatory actuator movable upon the frame, and connections between the actuator and separator continuously effective during the oscillation of the raceway. 30
35. In a nail-distributor, a frame, a raceway arranged to oscillate upon the frame, a nail-separator movable upon the raceway, a discharge device movable upon the raceway, an actuator movable upon the frame, and connections between the actuator and the separator and discharge device continuously effective during the oscillation of the raceway. 35
36. In a nail-distributor, a frame, a raceway arranged to oscillate upon the frame, a reciprocatory nail-separating plate mounted to slide upon the raceway, and an actuating slide movable upon the frame, the actuating slide and separating-plate having contacting surfaces through which the actuating movement is communicated to the plate. 40
37. In a nail-distributor, a frame, a raceway arranged to oscillate upon the frame, a reciprocatory nail-separating plate mounted to slide upon the raceway, a roll rotatable at the end of the raceway to receive and discharge nails therefrom, an actuating slide movable upon the frame, and gearing for rotating the roll, the actuating slide and the separating plate and gearing respectively having contacting surfaces through which the actuating movement is transmitted. 45
38. The combination with a nailing machine, of a nail-distributor, a raceway, a rotatable roll for discharging the nails from the raceway, a spring acting to rotate the roll, a latch for the roll, and means operable by the nailing machine to release the latch. 50
39. The combination with a nailing machine, of a nail-distributor having a frame, a raceway movable upon the frame, a nail-separator mov- 55
- able upon the raceway, a slide movable upon the frame and having a portion contacting with the separator, and a member operable by the nailing machine for governing the slide. 60
40. The combination with a nailing machine, of a nail-distributor having a frame, a raceway movable upon the frame, a nail-separator movable upon the raceway, a slide movable upon the frame and having a portion contacting with the separator, a member operable by the distributor 10 for actuating the slide, and means operable by the nailing machine for rendering said member effective. 65
41. The combination with a nailing machine, of a nail-distributor having a frame, a raceway movable upon the frame, a nail-separator movable upon the raceway, a nail-discharging device movable upon the raceway, gearing for rotating the discharging device, a slide movable upon the frame and having portions contacting with the separator and with the gearing, a member movable into engagement with the slide for actuating it, and means for producing the engaging movement. 70
42. The combination with a nailing machine, of a nail-distributor having a frame, a raceway movable upon the frame, a nail-separator movable upon the raceway, a nail-discharging device movable upon the raceway, gearing for rotating the discharging device, a slide movable upon the frame and having portions contacting with the separator and with the gearing, a spring by which the slide is moved, a latch for the gearing, a hook operable by the distributor and arranged for engagement with the slide, and a member movable by the nailing machine for causing the engagement of the hook with the slide and for releasing the latch. 75
43. In a nail-distributor, a raceway, a discharge device receiving nails from the raceway, and a nail-retaining projection carried by the discharge device and movable thereby into and out of the raceway. 80
44. In a nail-distributor, a raceway, a discharge-roll mounted for oscillation at the end of the raceway, and a stop projecting from the roll and movable into and out of nail-retaining relation to the raceway. 85
45. In a nail-distributor, a raceway, a discharge-roll mounted for oscillation and provided with a nail-passage movable between a position in which it will receive nails from the raceway and one in which it delivers said nails, and a stop-finger fixed upon the roll and movable thereby into active position in the raceway when the roll is in nail-delivering position. 90
46. In a nail-distributor, a movable raceway, a movable support for the raceway, and a nail-conduit mounted upon the support. 95
47. In a nail-distributor, an oscillatory raceway, a rocker-arm upon which the raceway is supported, and a tube mounted upon the rocker-arm and receiving nails from the raceway. 100
48. In a nail-distributor, an oscillatory raceway, a rocker-arm upon which the raceway is supported, a holder separably secured to the rocker-arm, and a plurality of tubes mounted upon the holder and to which the raceway delivers. 105
49. In a nail-distributor, an oscillatory raceway, a rocker-arm upon which the raceway is supported, a holder separably secured to the rocker-arm, a plurality of tubes mounted upon the holder and to which the raceway delivers, flexible tubes depending from the tubes upon the holder, 110

a foot-plate provided with movable tubes into which the flexible tubes extend, and means arranged to adjust the foot-plate-tubes to correspond to different nailing designs.

5. 50. In a nail-distributor, a raceway from which nails are delivered, conduits receiving the nails from the raceway and terminating in sections movable to different positions, a nail-retaining member movable with each terminal section, and actuating means movable into engagement with the retaining members.

51. In combination, nail transferring means, nail-conducting tubes, a foot-plate to which said tubes lead, tubes movable upon the foot-plate and receiving the nails for delivery to the transferring means, and a shutter individual to each foot-plate-tube and movable therewith.

52. The combination with nailing mechanism, of nail-supplying means having nail-holders movable into different positions, a nail-retaining member movable with each holder, and means common to the nail-holders for moving the retaining means.

53. The combination with nailing mechanism, of nail-supplying means having nail-holders movable into different positions, a nail-retaining member movable with each holder, and a member movable into engagement with the nail-holders for actuating them.

54. In a nail-distributor, nail-conducting tubes, a foot-plate to which said tubes lead, said foot-plate being provided with slots, tubes movable in the slots and receiving nails, a shutter individual to each tube and movable therewith, and an actuating plate movable upon the foot-plate and having a slot acting upon each shutter.

55. In a nail-distributor, nail-conducting tubes, a foot-plate to which said tubes lead, said foot-plate being provided with slots, tubes movable in

the slots and receiving nails, a shutter individual to each tube and movable therewith, each shutter having a projection, and an actuating plate movable upon the foot-plate and having slots registering with the foot-plate-slots and slots parallel thereto to receive the shutter-projections. 5

56. In a nail-supplying apparatus, a nail-transferring member, a nail-holder separably mounted upon the transferring member and having a plurality of nail-receiving passages, and a nail-retaining member movable upon the nail-holder to open and close the passages and separable with said holder from the transferring member. 10

57. In a nail-supplying apparatus, a nail-transferring member, a nail-holder separably mounted upon the transferring member and having a plurality of nail-receiving passages, and a plate movable upon the holder and separable therewith from the transferring member, said plate having openings which may be brought into registration 20 with the nail-passages of the holder.

58. In a nail-supplying apparatus, a nail-loader, a loader-block separably mounted upon the loader and provided with nail-receiving passages, and a shutter movably mounted upon the 25 block in co-operation with the passages, said shutter being separable from the loader with the block.

59. In a nail-supplying apparatus, a nail-loader, a loader-block separably mounted upon the loader and provided with nail-receiving passages arranged in accordance with a particular nailing design, and a shutter-plate individual to the block and movably mounted thereon, said shutter-plate having nail-discharging openings 35 arranged according to the same design as the block-openings.

FRED L. MACKENZIE.
